UNITED STATES PATENT OFFICE

IRVING T. GILLIAN, OF DETROIT, MICHIGAN

VEHICLE BODY CONSTRUCTION

Application filed September 13, 1928. Serial No. 305,665.

This invention relates to vehicle bodies and particularly to the pillars thereof and door dovetails employed in connection with them, the principal object being the provision of a new and novel construction, simple in design and economical to manufacture.

Another object is to provide a door dovetail particularly adaptable for use in connection with metal pillars and which will permit ready servicing of the dovetail.

Another object is to provide a door pillar and a dovetail so constructed that the pillar serves as one face of the dovetail and so receives the dovetail parts that they may be easily and quickly removed as a unit from the pillar.

A further object is to provide in combination with a metal pillar or a pillar provided with a metallic cover, a dovetail comprising a metal casing open on one side and enclosing the usual dovetail parts, the pillar being provided with an opening in which the dovetail is receivable as a unit, and the dovetail being provided with flanges for removably attaching it to the pillar.

The above being among the objects of the present invention, the same consists in certain features of construction and combinations of parts to be hereinafter described with reference to the accompanying drawings, and then claimed, having the above and other objects in view.

In the accompanying drawings which illustrate a suitable embodiment of the present invention, and in which like numerals refer to like parts throughout the several different views,—

Fig. 1 is a horizontal sectional view taken through the pillar for a motor vehicle at the point where a dovetail is secured thereto.

Fig. 2 is a fragmentary perspective view of the pillar with the dovetail removed.

Fig. 3 is a side view of the dovetail shown in mounted position on a fragment of the pillar one face of which is shown removed to show the assembly of parts of the dovetail.

Fig. 4 is a view of the blank for the dovetail casing or container before bending.

Fig. 5 is a view similar to Fig. 1 but showing the adaptation of the present invention

to a wooden pillar provided with a metallic facing.

Pillars for motor vehicles formed from sheet metal are coming into relatively wide use. One problem that has arisen in connection with such pillars is the method of securing the door dovetails to them. At the present time the container or members employed for holding the various parts of the dovetail together are secured to the pillar in either one of two ways. The first is by welding the casing to the inside face of the pillar and depending upon the usual opening provided for the reception of the male member of the dovetail for permitting insertion and removal of the various parts of the female member into and from the container. The second method is to removably attach the casing and the dovetail parts from the inside of the pillar. In the first of these methods because of the relatively small opening necessitated there is considerable difficulty in readily and properly inserting the dovetail parts through the opening for the male member, and in the second of these methods, in order to remove a dovetail and replace the parts thereof the interior trim on the pillar must be first removed to permit access to the interior of the pillar. Neither of these methods are at all satisfactory from a service standpoint as the expense involved in replacing the worn parts of a dovetail is usually not commensurate with the benefits derived.

The principal object of the present invention is to provide a simple and economical construction for securing the female member of a dovetail in a door pillar which will permit the dovetail to be easily and quickly removed and replaced. In accordance therewith I show in the accompanying drawings a pillar of conventional construction for an automobile body and formed of sheet metal. This pillar comprises the side portions 10, the inwardly bent portions 11, side portions 12 and face portion 13. A U-shaped sheet metal member 14 is secured between the free edges of the side portions 10 by welding or other suitable means and received within the member 14 is a wooden strip 15 which serves as the

tacking strip for the upholstery or other interior trim of the vehicle body. In Figs. 1 and 2 I show a dovetail applied to one side only of the pillar, it being obvious that another dovetail may be applied to the opposite side of the pillar in exactly the same way, and that instead of a pillar of the type described the present invention is also equally well adapted for use in connection with any other type of sheet metal pillar construction. In accordance with the present invention the side face 10 of the pillar is notched out as at 16 to provide clearance for the conventional male member (not shown) of the dovetail which is received therein when the door (not shown) is in closed position, as is readily obvious to those skilled in the art. In conventional constructions the face 11 is provided with a notch across its width in alignment with the notch 16 and of the same width for passage of the male member through such face. In the present invention instead of providing such relatively narrow notch I cut away the face 11 on either side of the notch 16 to provide a relatively deep opening 17 extending from a point a substantial distance above the notch 16 to a point a substantial distance below the notch 16, the vertical distance being commensurate with the vertical depth of the door dovetail which is to be received therein. This door dovetail may take the form illustrated in Figs. 1 and 3 and is preferably formed of sheet metal to provide a casing or container having a side 18, ends 19, back 20 and flange faces 21, the one side being left entirely open. The flange faces 21 project above and below the end faces 19 and are separated at their inner ends by an amount substantially equal to the width of the notch 16. The distance between the outer faces of the ends 19 is slightly less than the depth of the opening 17 in the pillar, and the casing is of a slightly less thickness than the width of the opening 17 so that it is readily receivable therein. Within the casing may be positioned the usual dovetail parts of any conventional construction, that shown comprising the rubber blocks 22 and spring wear member 23 between which the male member of the dovetail is adapted to be resiliently clamped when the door is in closed position. The face 11 of the pillar is preferably depressed as at 24 immediately above and below the opening 17 an amount equal to the thickness of the projecting portions of the face flanges 21 and for a distance away from the opening 17 an amount commensurate with the distance which the flange faces 21 project away from the ends 19 so that when the dovetail is inserted in place, the outer surface of the flange faces 21 will lie flush with the outer surface of the face 11. The depressed portions 24 are then provided with openings 25, the walls of which may be threaded or which may be provided with nuts

27 secured to the rear face of the portions 24 in alignment with the openings 25 by welding or other suitable means. The flange faces are provided with matching openings 26. In assembling the dovetail to the pillar the same is inserted through the opening 17 into the interior of the pillar, the projecting ends of the flange faces being received in the depressions 24 and suitable screws 32 being inserted through the openings 26 and threaded into the nuts 27, thereby securing the dovetail in place. The notch 16, when the dovetail is in assembled position on the pillar, is in alignment with the space between the spring members 23 and the open side of the container is otherwise closed by the side face 10 of the pillar, thus preventing displacement of the rubber blocks 22 and spring members 23. I also find it preferable to secure a flange member 28 to the back 20 of the container and insert a screw 29 through an opening 30 provided in the face 10 and either threaded directly into the member 28 or a nut such as 31 secured thereto by welding or other suitable means. This firmly holds the dovetail in assembled position in the pillar.

It will be apparent from the above that when the spring members 23 or rubber blocks 22 become worn or otherwise damaged and replacement of the same is necessary, it is only necessary to remove three screws and remove the container with such parts from the pillar, after which the parts in the container may be replaced and the assembly again replaced and secured in the pillar. This construction makes an ideal servicing proposition and one that is not only economical in production but is relatively inexpensive in service as far as the owner of the vehicle is concerned.

The casing itself may be made in any suitable manner but in Fig. 4 I illustrate a method by which it may be formed in a simple and economical manner. As illustrated in that figure, a sheet of metal is stamped out to the shape shown and is sheared as at 33. The blank is then bent about the lines 34 to form the ends 19, bent about the line 35 to form the back 20, and bent about the line 36 to form the flange faces 21, thus leaving the side face 18. The side portions 19 and back 20 are preferably provided with tongues such as 37 and 38 respectively which, after the blank has been bent as above described, may be bent around the adjacent sides as indicated in Fig. 3, and welded or otherwise secured to such sides to thus secure the sides and back against separation.

The above described construction is equally well applicable to those pillar constructions in which the pillar is formed of wood such as 40 in Fig. 5 to the general contour of the pillar previously described and is provided with a sheet metal sheathing 41. In such a case the wooden portion 40 before ap-

lication of the sheathing 41 is provided with a notch such as 42 at the point where each dovetail is to be applied to it. The sheathing 41 before assembly to the wooden portion 40 is first cut away in the same manner as the all-metal pillar previously described and as indicated in Fig. 2, and thereafter the dovetail is secured to the metallic portion of the pillar, and to the wood in addition if desired, as will be readily apparent and as indicated in Fig. 5.

Formal changes may be made in the specific embodiment of the invention described without departing from the spirit or substance of the broad invention, the scope of which is commensurate with the appended claims.

What I claim is:

1. In combination with a door pillar provided with a pair of connected sheet metal walls extending at an angle to each other, one of said walls being provided with a notch extending perpendicularly to the line of junction of said walls, the other of said walls being provided with an opening joining said notch and extending beyond either side thereof, a female member of a door dovetail including a metal casing and opposed blocks insertable through and removable from said opening positioned within said pillar, said casing being provided with a flange overlying an exterior face of said pillar, and removable means securing said flange to said face.

2. In combination with a door pillar provided with a pair of connected sheet metal walls extending at an angle to each other, one of said walls being provided with a notch extending perpendicularly with respect to the line of junction of said walls, the other of said walls being provided with an opening joining said notch and extending to points beyond either side thereof, a female door dovetail member including a casing insertable into and removable from said pillar through said opening positioned within said pillar, said casing being open on that side thereof adjacent said notch and such open side being otherwise closed by said wall in which said notch is provided, and removable means securing said casing against movement in said pillar.

3. In combination, an approximately trough shaped door pillar formed from sheet metal and provided with a pair of walls extending at approximately right angles to each other, one of said walls being provided with a notch therein extending from the line of junction of said walls in a direction perpendicular to said line of junction, the other of said walls being provided with an opening therein joining said notch and extending beyond the sides of said notch in both directions and in parallel relation with respect to said line of junction, a door

dovetail female member comprising an open faced sheet metal casing having a pair of oppositely extending flanges at one end thereof and an outwardly extending flange at the other end thereof, a pair of opposed blocks within said casing forming a recess between them, said casing being removably received in said pillar through said opening with said pair of flanges contacting against the outer face of said other wall and the other of said flanges contacting against the inner face of the first mentioned wall, said flanges and said opening locating said casing relative to said notch whereby said blocks are disposed on opposite sides of said notch, and removable means securing said flanges to said pillar.

4. In combination with a door pillar provided with a pair of connected sheet metal walls extending at an angle to each other, one of said walls being provided with a notch extending perpendicularly with respect to the line of junction of said walls, the other of said walls being provided with an opening joining said notch and extending to a point beyond at least one side thereof, a female door dovetail member including a casing insertable into and removable from said pillar through said opening positioned within said pillar, said casing being open on that side thereof adjacent said notch and such open side being otherwise closed by said wall in which said notch is provided, and removable means securing said casing against movement in said pillar.
